CLAIM

I claim the ornamental design for a double scarf, as shown and described.

DESCRIPTION

FIG. 1 is a perspective view of a double scarf, showing a first embodiment of my new design in an overlapping configuration;

FIG. 2 is a front elevational view thereof, illustrated in an extended configuration

FIG. 3 is a rear elevational view of FIG. 2;

FIG. 4 is a right-side elevational view of FIG. 2;

FIG. 5 is a left-side elevational view of FIG. 2;

FIG. 6 is a top plan view of FIG. 2;

FIG. 7 is a bottom plan view of FIG. 2;

FIG. 8 is a perspective view of a second embodiment thereof, illustrated in the overlapping configuration;

FIG. 9 is a front elevational view of the second embodiment in the extended configuration;

FIG. 10 is a rear elevational view of FIG. 9;

FIG. 11 is a right-side elevational view of FIG. 9;

FIG. 12 is a left-side elevational view of FIG. 9;

FIG. 13 is a top plan view of FIG. 9; and,

FIG. 14 is a bottom plan view of FIG. 9.

The broken lines showing a person in FIGS. 1 and 8 depict environmental matter and form no part of the claimed design.
